UNITED STATES PATENT OFFICE.

JOHN MILLS, OF BRANTFORD, CANADA.

DENTAL MATRIX-RETAINER.

SPECIFICATION forming part of Letters Patent No. 719,834, dated February 3, 1903.

Application filed September 5, 1902. Serial No. 122,236. (No model.)

To all whom it may concern:

Be it known that I, JOHN MILLS, L. D. S., of the city of Brantford, in the county of Brant and Province of Ontario, Canada, have invented certain new and useful Improvements 5 in Dental Matrix-Retainers, of which the following is a specification.

The object of my invention is to devise means for retaining in position the band or 10 matrix used to form the outer wall of a cavity in the side of a tooth when putting in a filling; and it consists, essentially, of two holders pivoted by ball-and-socket joints on the inner ends of a pair of T-levers, which 15 are centrally pivoted together and are provided between their outer ends with a spring, tending to force the inner ends together, and means for locking the levers to cause them to rigidly hold the holders from spreading apart 20 after being adjusted to the matrix, substantially as hereinafter more specifically described and then definitely claimed.

Figure 1 is a plan view of my improved matrix-retainer, full size. Fig. 2 is an enlarged 25 perspective detail of the holders, parts being shown separated. Fig. 3 is an enlarged perspective front view of one of the holders. Fig. 4 is an enlarged perspective detail of the means employed for locking the levers, the 30 parts being shown separated. Fig. 5 is an enlarged cross-section through the sleeve and expansion-plug of the lock.

In the drawings like letters of reference indicate corresponding parts in the different 35 figures.

Referring particularly to Fig. 1, A A are a pair of substantially T-shaped levers. The lugs *a a*, forming the stems of the T, are pivoted together at *b*. The inner end of each 40 lever has a holder *B*, pivoted thereto by means of a ball-and-socket joint, the ball *c* being connected by a short stem with the end of the lever and the socket being formed partly in the holder *B* and partly in the cap 45 *C*, secured thereto by screws or in any other suitable manner. The stems of the balls are connected to the ends of the levers by being soldered or shrunk into holes formed at their ends. Each holder has its face formed with 50 two concave curves meeting in a central cusp. By reference to Fig. 3 it will be seen that the lower point of the cusp projects some-

what more than the upper point. I find this construction very advantageous, as while most teeth are somewhat bell-shaped, so that 55 the holders fit best with the most extended point of the cusp lowermost, still others are best fitted when the most extended point of the cusp is uppermost. As the ball-and-socket joints permit the holders to be easily 60 reversed, the latter may be easily fitted to suit the requirements of either type of teeth. It will be noticed also that the faces of the holders are slightly concave in a vertical section to enable them to fit closely the vertical 65 curves of the teeth with which they may be engaged. At the outer end of one of the levers I hinge a nut *D*, through which is screwed an expanding-screw *E*. This expanding-screw also screws within the upper end of the 70 expansion-plug *F*, which is provided with a bore tapered toward the lower end of the split portion of the plug. (See Figs. 4 and 5.) This expansion-plug fits within the sleeve *G*, which has a short spindle *d* formed thereon, extending 75 through the end of the lever *A*. On the end of this spindle a milled head *E* may be secured detachably or otherwise for convenience in handling the instrument. A flange *f* is preferably formed on the expansion-plug *F*, bearing 80 against the nut *D*, hinged on one of the levers *A*. A similar flange *g* is formed on the sleeve *G*, bearing against the other lever *A*. Between these flanges is located a compression 85 coil-spring *H*, which tends normally to expand the outer ends of the levers, and thus cause the holders to firmly grip the tooth with which they are engaged, as shown in Fig. 1. In this figure a matrix *h* is shown in position to form the outer wall of a cavity in 90 a tooth. This matrix is retained in position by the pressure of the two holders *B*, which are forced between the two teeth by the pressure of the coil-spring *H*. If it be desired to give additional security, by turning the milled 95 head *i* of the expansion-screw *E* the expansion-plug *F* may be expanded within the sleeve *G*, causing the two to lock together in an ordinary manner to retain the lower ends of the levers in the position into which they 100 have been brought by the spring. The holders *B* are thus rigidly held from spreading apart. When the plug is tight within the sleeve, the continuous turning of the expand-

ing-screw will turn both plug and sleeve, and the screw turning in the nut D will put a positive strain on the levers, and thus relieve the spring of the responsibility of holding the 5 matrix in position. While I prefer to hinge the nut D to the end of the lever A, yet this construction is not absolutely essential, as by making the threads therein a little slack for the screw E sufficient play may be given to 10 allow the screw to adjust itself to the varying positions of the nut due to the opening and closing of the levers.

While I have described my invention in detail, I desire it to be understood that I do not 15 wish to be confined to the exact construction described, as many variations in detail might be made without departing from the spirit of my invention.

What I claim as my invention is—

20 1. In a dental matrix-retainer a pair of levers pivoted together, in combination with a pair of holders one pivoted at the inner end of each lever by a ball-and-socket joint; and a spring connecting the levers and normally 25 tending to force the holders toward one another, substantially as described.

2. In a dental matrix-retainer a pair of T-levers centrally pivoted together, in combination with a pair of holders, one pivoted at the 30 inner end of each lever, and a compression coil-spring suitably arranged between the outer ends of the levers, substantially as described.

3. In a dental matrix-retainer a pair of levers pivoted together, in combination with a pair of holders, one pivoted at the inner end of each lever by a ball-and-socket joint; a spring connecting the levers and normally tending to force the holders toward one another; and an adjustable lock connecting the levers by means of which the levers may be locked to prevent the holders spreading after they have been adjusted to a matrix, substantially as described.

45 4. In a dental matrix-retainer a pair of T-levers centrally pivoted together, in combination with a pair of holders, one pivoted at the inner end of each lever; a compression coil-spring suitably arranged between the outer 50 ends of the levers; and an adjustable lock connecting the levers by means of which the levers may be locked to prevent the holders spreading after they have been adjusted to a matrix, substantially as described.

55 5. In a dental matrix-retainer a pair of levers provided with central lugs pivoted together, in combination with a pair of holders, one pivoted at the inner end of each lever; and a compression coil-spring suitably 60 arranged between the outer ends of the levers, substantially as described.

6. In a dental matrix-retainer a pair of T-

levers centrally pivoted together, in combination with a pair of holders, one pivoted at the inner end of each lever; a sleeve connected 65 with the outer end of one lever; an expansion-plug with a tapered bore engaging the outer end of the other lever and entering the aforesaid sleeve; and an expanding-screw passing through the end of the last-mentioned lever 70 and screwed into the end of the plug, substantially as described.

7. In a dental matrix-retainer a pair of T-levers centrally pivoted together, in combination with a pair of holders, one pivoted at the 75 inner end of each lever; a sleeve connected with the outer end of one lever; an expansion-plug with a tapered bore engaging the outer end of the other lever and entering the aforesaid sleeve; an expanding-screw passing 80 through the end of the last-mentioned lever and screwed into the end of the plug and a compression coil - spring surrounding the sleeve and plug engaging the ends of the levers, substantially as described. 85

8. In a dental matrix-retainer a pair of T-levers centrally pivoted together, in combination with a pair of holders, one pivoted at the inner end of each lever by a ball-and-socket joint; a sleeve connected with the outer end 90 of one lever, an expansion-plug, with a tapered bore engaging the outer end of the other lever and entering the aforesaid sleeve; an expanding-screw passing through the end of the last-mentioned lever and screwed into the 95 end of the plug and a compression coil-spring surrounding the sleeve and plug engaging the ends of the levers, substantially as described.

9. In a dental matrix - retainer in which 100 holders are operated by pivoted levers a holder having a face formed with two concave curves joining in a central cusp, one point of the cusp being extended outwardly farther than the other, in combination with a ball - and-socket connection between the holder and 105 one of the levers permitting the holder to be moved to any desired position, substantially as described.

10. In a dental matrix-retainer a pair of T-levers centrally pivoted together, in combination with a pair of holders, one pivoted at the inner end of each lever; a sleeve connected with the outer end of one lever; a nut hinged to the outer end of the other lever; an expansion-plug with a tapered bore entering the 115 aforesaid sleeve, and an expanding-screw threaded to screw through the nut and into the end of the plug, substantially as described.

Brantford, August 30, 1902.
